UNITED STATES PATENT OFFICE.

HENRY S. SLOAN, OF MILWAUKEE, WISCONSIN, ASSIGNOR TO WASTE PRODUCTS PULP COMPANY, OF DETROIT, MICHIGAN, A CORPORATION OF SOUTH DAKOTA.

PULPER.

1,283,931.

Specification of Letters Patent.

Patented Nov. 5, 1918.

Application filed December 22, 1916. Serial No. 138,378.

To all whom it may concern:

Be it known that I, HENRY S. SLOAN, citizen of the United States, residing at Milwaukee, county of Milwaukee, and State of Wisconsin, have invented new and useful Improvements in Pulpers, of which the following is a specification.

My invention relates to improvements in pulpers.

10 The object of my invention is to provide means for macerating vegetable fiber, such as corn stocks and other material adapted for the manufacture of paper and other articles in which fibrous material is employed.

15 It is well known that vegetable fibers are easily broken and destroyed where ordinary pulping mechanism is employed and the object of my invention, more specifically stated, is to provide means for pulping vegetable growths in which the breakage and destruction of the fiber will be reduced to a minimum.

In the drawings—

20 Figure 1 is a general elevation of my invention with a pulping vat illustrated in vertical section.

Fig. 2 is a view of the vat and its supporting truck drawn at right-angles to Fig. 1.

Like parts are identified by the same reference characters in both views.

25 The pulping operation is performed in a vat A, which may be mounted upon a truck or any suitable vehicle having wheels B, whereby the vat may be transferred from place to place and used in any field where vegetable growths are to be operated upon.

30 In the construction illustrated in the drawing, the vehicle axle C is offset and allows the vat A to be supported between the wheels 40 B of a two-wheeled truck, and the axle is provided with a set of upwardly projecting standards D, having bearings at d in which stud shafts E are journaled, said shafts being connected with the wheels of the vat, as shown.

35 A plunger F is located within the vat A and is provided with a series of depending pulping balls or weights F', each yieldingly supported from the plunger by a rod f extending loosely through an aperture in the plunger and provided with a head f' at its upper end. Springs G are coiled about each of the rods f and interposed between the balls or weights F' and plunger F. The 45 rods are adapted to slide upwardly through

the plunger when the balls or weights encounter resistance, the springs offering increasing resistance to the upward movement. Said springs are also adapted, by their recoil, to actuate the pulping balls or weights 60 downwardly with considerable violence after a period of spring compression, and after the resistance has ceased, which caused such a compression. It is therefore obvious that, when the plunger F is reciprocated vertically to bring the balls or weights F' into successive hammering contacts with a quantity of vegetable fiber within the vat, each of the balls will be allowed to strike upon the contents of the vat substantially with hammer blows, the force being substantially equal to its own momentum, since the springs, when distended, will offer but little resistance to the upward movement of the ball.

75 It will also be observed that, owing to the fact that the stems f extend loosely through the plunger apertures, the balls or weights F' will be permitted to swing from side to side or forwardly or backwardly, whereby 80 they will collectively reach all portions of the material within the vat, and whereby also they will be permitted, when striking raised bodies of material, to move toward one side thereof and again strike other materials at lower levels under the recoil of the spring encircling the stem of such ball. I 85 preferably use weights in the form of balls, since the rounded surfaces thus presented reduce breaking effects upon the fiber to a 90 minimum.

A reciprocating motion may be imparted to the plunger by any suitable means. In the construction illustrated, a crank pin I, connected with the fly-wheel J of an engine 95 or motor, transmits motion to the plunger through the connecting rod K, lever L, a set of clutches M and a plunger actuating rod or stem N. The stem N is provided with a series of annular cogs or teeth n. 100 The clutches M are provided with similar teeth m and are supported from the end of lever L by a pivoted hanger rod O, connected with a cross bar P, which is attached to the extremity of the lever L at l. A 105 spring O' tends to hold hangers O with the clutches M in position of engagement with the teeth n on the plunger actuating rod or stem N. But when the plunger is in raised position, the clutches M are sepa- 110

rated and retracted from the plunger rod or stem N, this being accomplished by providing each of the hangers O with a bracket Q having a knob Q' attached to engage a 5 relatively fixed guide R, when the plunger is raised, said guide being positioned for movement of the bracket knob Q upwardly and outwardly along its outer face.

The brackets R are secured to a frame bar 10 R'. The lever L is secured to a frame post L' and its long arm is connected with the cross bar P, whereby a stroke of considerable length may be imparted to the plunger F.

15 I do not limit the scope of my invention to the specific construction illustrated. Particularly the specific means for actuating the plunger is not essential, but I prefer to employ means for lifting the plunger to a 20 predetermined height and then allowing it to drop by gravity, whereby substantially uniform blows will be struck by the balls or weights F' upon the material within the vat A. It is obvious that, if the plunger were 25 moved downwardly by means of the lever L, the force with which the material in the vat would be struck would depend very largely upon the quantity of the material, or upon the height to which portions of the 30 material may extend, and it would be difficult to provide yielding connections which would overcome these variances in the force of the blows imparted to the material sufficiently to avoid breaking the fiber on one 35 hand or failing to pulp it on the other hand.

I have also discovered that there is a great advantage in allowing the plunger to drop by gravity owing to the fact that each of the weights or balls acquires considerable 40 momentum and a quick hammer blow is imparted to the material, which is very effective in causing a separation of the fiber from the intervening bodies of cellulose.

45 The contents of the vat are preferably heated preparatory and during the pulping operation. I therefore provide a fire-pot or burner S. Any suitable fuel may be employed to heat the contents of the vat.

I claim—

50 1. Pulping mechanism including the combination with a heating vat, of a set of macerating weights therein, and means for intermittently lifting the weights and allowing them to drop by gravity upon the material.

55 2. Pulping mechanism including the combination with a heating vat, of a set of macerating weights therein, and means for simultaneously lifting the weights and subsequently allowing them to drop by gravity upon the material.

60 3. Pulping mechanism including the combination with a heating vat, of a set of macerating weights therein, and means for simultaneously lifting the weights and sub-

sequently allowing them to drop by gravity upon the material, said weights being free for limited independent dropping movements, whereby each may exert the force of its own impact upon the material independently of the others. 70

4. Pulping mechanism including the combination with a vat, of a vertically movable plunger therein, a set of weights loosely suspended from the plunger, and adapted to 75 move to a limited extent both laterally and vertically with reference to the plunger and to each other, and means for vertically reciprocating the plunger.

5. Pulping mechanism including the combination with a vat, of a vertically movable plunger therein, a set of weights loosely suspended from the plunger, and adapted to move to a limited extent both laterally and vertically with reference to the plunger and to each other, and means for vertically reciprocating the plunger, said plunger reciprocating means including a vertically moving clutch adapted to intermittently lift and release the plunger, whereby 90 the latter is permitted to drop after each lifting operation. 80

6. Pulping mechanism, including the combination with a vat, a plunger therein provided with a toothed operating rod, a vertically reciprocating clutch adapted, when depressed, to engage said rod, and means for releasing the clutch from the rod when in its raised position, to allow the plunger to 95 drop by gravity. 100

7. Pulping mechanism, including the combination with a vat, a plunger therein provided with a toothed operating rod, a vertically reciprocating clutch adapted, when depressed, to engage said rod, and means for 105 releasing the clutch from the rod when in its raised position, to allow the plunger to drop by gravity, said plunger being provided with a set of loosely connected depending weights, each adapted for independent impact with the material when the plunger is dropped. 110

8. Pulping mechanism, including the combination with a vat, a plunger therein provided with a toothed operating rod, a vertically reciprocating clutch, adapted, when depressed, to engage said rod, and means for releasing the clutch from the rod when in its raised position, to allow the plunger to drop by gravity, said plunger being provided with 115 a set of loosely connected depending weights, each adapted for independent impact with the material when the plunger is dropped, and means for resiliently opposing relative movements of the plunger and weights toward each other. 120

9. Pulping mechanism, including the combination with a vat, a plunger therein provided with a toothed operating rod, a vertically reciprocating clutch adapted, when 130

depressed, to engage said rod, and means for releasing the clutch from the rod when in its raised position, to allow the plunger to drop by gravity, said weights being spherically rounded and each having a stem loosely mounted to slide through the plunger.

10. Puling mechanism, including the combination with a vat, a plunger therein provided with a toothed operating rod, a vertically reciprocating clutch adapted, when depressed, to engage said rod, and means for releasing the clutch from the rod when in its raised position, to allow the plunger to drop by gravity, said weights being spherically rounded and each having a stem loosely mounted to slide through the plunger, from which the weights are nor-

mally held in extended position by springs coiled about said stems. 20

11. Puling mechanism including the combination with a portable vat, of a series of spherically rounded weights, means for simultaneously lifting said weights, and means for allowing each of said weights to drop by gravity independently of the others to a sufficient extent to allow each to exert free impact upon the material due to its momentum.

In testimony whereof I affix my signature 30 in the presence of two witnesses.

HENRY S. SLOAN.
